UNITED STATES PATENT OFFICE

ALBERT L. IDE, OF SPRINGFIELD, ILLINOIS.

VALVE-INDICATOR.

SPECIFICATION forming part of Letters Patent No. 322,723, dated July 21, 1885.

Application filed February 18, 1885. (No model.)

To all whom it may concern:

Be it known that I, ALBERT L. IDE, of Springfield, in the county of Sangamon and State of Illinois, have invented certain new and useful Improvements in Valve-Indicators; and I do hereby declare that the following is a full, clear, and exact description thereof, reference being had to the accompanying drawings, and to the letters of reference 10 marked thereon, which form a part of this specification.

My invention is herein illustrated in connection with a steam-engine similar to that shown in an application for Patent No. 125,672, 15 made by me upon the 27th day of March, 1884. The said engine is of that class intended to run at a high rate of speed, and having automatic cut-off mechanism for using steam expansively, the said engine being provided 20 with a governor constructed to automatically control the movements of the steam-valve, so as to cut off the supply of steam to the cylinder when the speed for which the governor is adjusted is exceeded, and to admit steam 25 through a greater part of the stroke when the speed of the engine is decreased by an increase of resistance.

The governor herein illustrated is of that class known as "fly-wheel" governors, or in 30 which the eccentric which actuates the valve is made laterally movably upon the shaft in such manner as to vary the throw of the eccentric-rod, and wherein the eccentric is connected with arms pivoted to the fly-wheel 35 and provided with adjustable weights, which tend by their centrifugal action to move the eccentric in a direction to shorten the throw of the rod, and thereby lessen the movement of the valve when the speed of the engine is 40 increased, the outward movement of the said weights being controlled by springs constructed to hold the eccentric normally at a point which gives the valve full throw, and which are so adjusted with reference to the 45 weights that upon any increase of the speed beyond that desired the weights will be thrown outwardly in opposition to the force of the springs, and thereby shorten the throw of the valve, and upon any decrease of the 50 speed caused by additional resistance the springs will draw the weights inwardly, so as to give a longer throw to the valve, and there-

by permit the steam to follow the piston through a greater part of the stroke.

In all engines using steam expansively, 55 either by means of the cut-off mechanism herein described or otherwise, it is desirable to have means whereby the operator may ascertain the point of the stroke at which the steam is cut off, this being usually and conveniently expressed in the number of inches traveled by the piston with the steam at full boiler-pressure. For this purpose it is proposed by this invention to place an index hand or pointer upon the valve-rod or one of 65 the operative parts of the valve-gearing connected therewith, which pointer is arranged to move over a scale marked to indicate by the extent of the throw of the valve the number of inches of steam in the cylinder at the 70 moment the steam is cut off, whereby movements of such pointer will indicate to the eye at all times the condition under which the engine is operating, and thus enable the boiler-pressure to be regulated so as to obtain 75 the best results with the greatest economy in the use of steam. Such indicator also, in connection with the known steam-pressure and the speed of the piston, furnishes the necessary data whereby the work done or the 80 amount of power exerted by the engine, and expressed in horse-power or otherwise, may be readily calculated at any time.

The invention may be more readily understood by reference to the accompanying drawings, in which—

Figure 1 is a side or front elevation of an engine embodying my invention. Fig. 2 is an enlarged transverse section through the engine-frame, taken upon line x x of Fig. 1. 90 Fig. 3 is an enlarged detail section taken upon a vertical plane through the engine-cylinder and steam-chest upon line x x of Fig. 2.

The main frame or bed A of the engine shown in the said drawings is similar to that shown 95 in the application above referred to, and the steam-cylinder B is secured to the frame at one end of the latter in the same manner as shown in said application. The said engine is provided with a crank-shaft, C, having the usual bearing in the frame A, and provided with a crank-disk, C', having the usual crank-pin, c, and also with a balance or band wheel, C'', herein shown as provided with a fly-wheel

governor or regulator, C³. The cylinder B is provided with a piston, E, of any ordinary or preferred construction, to which is attached the piston-rod E', attached to a cross-head, F, 5 constructed to operate in the guides G and G', formed upon the engine-frame, said piston-rod being connected with the crank-pin c by means of a connecting-rod, F', in the usual manner.

10 H is the valve-casing or steam-chest, which is preferably located beneath the cylinder, and is provided with a slide-valve, I, which is, as herein shown, of the form known as a "hollow piston" valve, and is operated from an eccentric 15 upon the engine-shaft through the medium of the rock-shaft J, which is provided with an upwardly-projecting arm, J', connected with the usual eccentric-rod, said rock-shaft also being provided with a downwardly-projecting 20 arm, J², which is connected with the said valve I by means of a valve-rod, I', and connecting-rod I².

As a convenient means of constructing and operating an indicator of the character above 25 described in the engine herein shown, the hand or pointer O of the indicator is applied to the end of the rock-shaft J, through the medium of which the slide-valve is actuated, said pointer being arranged to operate in connection 30 with a curved scale, P, secured to the engine-frame concentrically with the said shaft. By this construction the hand or pointer O will obviously in all cases partake of the motion of the valve. The pointer O is conveniently attached to the shaft J in the construction herein shown by being placed over the square end of the said shaft and held thereon by the head J⁴ of a screw-plug, as clearly shown in Fig. 2. The said scale, as shown in Fig. 1, is provided 35 with a central blank space, which represents the lap of the valve, the division lines or graduations at either side of said blank space representing the extent of travel in the valve from its position at the time the ports begin 40 to open to the extreme limit of the stroke under the different relative positions of the valve and piston as determined by the action 45 of the governing device upon the valve. The central blank space obviously measures the movements of the valve when it is not moved far enough to admit any steam to the cylinder, and the limits of said blank space indicate the 50 positions of the valve at the moment the ports begin to open, and when the steam is cut off 55 the graduations upon either side of the blank space indicate the extent to which the valve is moved while the port is open and consequently the quantity of steam admitted to the cylinder during such time, it being entirely 60 obvious that the shorter the throw of the valve the quicker will be the cut off and the smaller the quantity of live steam admitted to the cylinder. The quantity of steam thus admitted may be most conveniently measured 65 by the number of inches of travel in the piston, (or, in other words, the inches of steam in the cylinder behind the piston at the mo-

ment the steam-supply is cut off,) and the scale is therefore preferably adapted to indicate the extent of movement in the valve past 70 the opening and cut-off points when the ports are opened to admit live steam sufficient in quantity to move the piston one, two, or three, or other number of inches, so that the extreme positions of the indicator upon the scale 75 so marked will at all times during the operation of the engine indicate the inches of steam in the cylinder at the moment the steam-supply is cut off.

In constructing the scale P the position of 80 the lines or graduations thereon may be most conveniently determined after the engine has been set up and the several parts thereof put together by first placing the valve at the two points of cut-off and marking the positions 85 of the pointer at such times, the marks thus made indicating the extent of the valve lap or central blank space of the scale. The piston is then placed at a distance of one inch from the end of its throw, the cut-off or governing devices are placed and secured in position to bring the valve and pointer at the point of cut-off, the crank-shaft is turned, and the extreme positions of the pointer under these conditions are marked upon the scale. 90 The piston is then placed at two inches from the end of its throw, the position of the governing device again changed and set so as to bring the valve at the point of cut-off with the piston in the position indicated, the shaft 100 rotated so as to give full throw to the valve, and the extreme limits of the movement of the pointer marked as before. The same process is repeated with the piston at three, four, five, &c., inches from the end of its throw, so 105 that there is finally marked upon the scale a series of graduations indicating, by the extent of movement of the valve, the number of inches of steam in the cylinder at the time the steam is cut off. 110

By the process described a scale is made in which all errors from calculation are eliminated, and which is accurate for each engine.

It is of course not essential that an oscillating pointer, as is herein shown, should be 115 used, inasmuch as a pointer or index attached directly to the valve-rod and moving over a straight scale or indicator attached to another part, which moves with the valve or valve-rod and which is used in connection with the scale 120 graduated as above set forth, will accomplish the general results herein described.

I am aware that it has been proposed heretofore to employ in valve-indicators a scale in connection with a pointer moving with the 125 valve to show the position of the latter with relation to the valve-ports, and I do not therefore claim, broadly, such indicator; but my invention, as it relates to the part mentioned, is restricted to an indicator graduated to show 130 the number of inches of steam in the cylinder when the steam is cut off, as set forth in the appended claims.

Improved results in point of simplicity and

economy of construction are obtained by attaching the index-hand of the indicator to the end of the rock-shaft, as shown, and this novel construction is also, therefore, herein 5 claimed.

I claim as my invention—

1. The combination, with the steam-valve of a steam-engine, of an indicator operated by the movement of the valve, and constructed to 10 show the number of inches of steam in the cylinder at the moment the steam-supply is cut off, substantially as described.
2. The combination, with the steam-valve of a steam-engine, of an indicator showing the 15 number of inches of steam in the cylinder at the time the steam-supply is cut off, comprising a pointer or index-hand operated by the movement of the valve, and a stationary scale or dial having a central blank space showing

the extent of the valve lap, and graduated 20 parts at either side of the blank space indicating the number of inches of steam in the cylinder at the moment the steam is cut off, substantially as described.

3. The combination, with the steam-valve 25 and eccentric-rod of a steam-engine, of a rock-shaft for transmitting motion from the said eccentric-rod to the valve provided with an index-hand and a stationary dial, substantially as and for the purpose set forth. 30

In testimony that I claim the foregoing as my invention I affix my signature in presence of two witnesses.
